United States Patent Office

Des. 217,908
Patented June 30, 1970

217,908

SEAT OR THE LIKE

Michel Boyer de Rebeval, 14 Rue Montmartre,
Paris, France

Filed Mar. 19, 1969, Ser. No. 16,318

Term of patent 14 years

Claims priority, application France Oct. 24, 1968

Int. Cl. D6—09

U.S. Cl. D15—8

The figure is a front perspective view of a seat or the like showing my new design.

A diagonally opposite view of the seat taken in perspective would have the same appearance as that shown.

I claim:

The ornamental design for a seat or the like, as shown and described.
